JOHN C. McLAUGHLIN, OF JERSEY CITY, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,064,081.

Specification of Letters Patent. Patented June 10, 1913.

Application filed April 5, 1912. Serial No. 688,594.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to a new and improved paper depth gage for a typewriter and is an improvement on my application No. 688,331, filed April 3, 1912.

It is the purpose of this invention to provide a simple, substantial and accurate paper depth gage whereby the typist can determine at a glance how close the bottom of the sheet is approached, and also whereby the typist can set a limit of approach to the bottom edge leaving any desired bottom margin. In other words, it enables the typist to set a limit to the number of lines to be written on a sheet, and to tell at a glance when this limit has been reached.

It is further the purpose of this invention to provide a gage which can be quickly detached when it is not desired to use the same and also which can be as readily snapped on into an operative position when it is necessary to use it.

In the present embodiment of the invention, the gage is shown to include a standard, attaching means and a stop. The standard is formed from a single strip of wire bent intermediate its ends to form an elongated loop with parallel reaches. The stop is adjustable along the standard and forms with the standard at the junction of the two, a stopping point for the top edge of the work sheet. When the work sheet comes in this position it is a signal that the predetermined limit of writing on the work sheet has been reached. The stop is resilient and formed to lock itself in its adjusted position on the standard by engaging with notches therein. Two forms of attaching means are herewith shown, one in which the attaching part is integral with the standard, and in fact formed from the same strip of wire, and the other in which this part is formed from a strip of sheet metal. In both cases, however, the attaching means is constructed of spring material and formed so as to readily snap into a locked position, as by squeezing between the rail and the paper shelf on the platen frame.

Other features and advantages will hereinafter appear.

In the accompanying drawings, Figure 1 is a vertical section taken from the front and rear of the top part of the typewriter, showing the gage in its attached position with the work sheet in a position corresponding to the writing of the last line of the typewritten matter. Fig. 2 is a fragmentary perspective view. Fig. 3 is a fragmentary view in front elevation showing the relation of the stop to the standard. Fig. 4 is a fragmentary vertical section on the line 4—4 of Fig. 3, showing the stop in its locked position. Fig. 5 is a view similar to Fig. 4 showing the stop flexed against the tension of the spring metal thereof, to assume its unlocked condition. Fig. 6 is a bottom plan view showing the relation of the stop to the standard in its locked position. Fig. 7 is a fragmentary rear view of a modified form of gage showing a modified means of attaching the gage to the typewriter. Fig. 8 is a fragmentary perspective view of the form shown in Fig. 7. Fig. 9 is a vertical transverse section of the form shown in Figs. 7 and 8.

Referring more particularly to the separate parts of this invention as embodied in the forms shown in the drawings, 1 indicates the typewriter or typewriting mechanism, only a part of which is, however, shown. The typewriter may include, as usual, a carriage having a platen frame 2, on which is rotatably mounted a platen 3 for supporting a work sheet 4. The work sheet 4 is struck by the type on the type-bars 5 when the latter are actuated in any usual manner by key mechanism, so that an imprint is made on the work sheet at a point 6, which may be termed the printing point of the typewriter.

Inasmuch as it is desirable that the number of lines written on a work sheet shall be limited, or in other words, that the bottom line of the typewritten matter shall be distant a certain amount from the bottom edge of the work sheet, it is necessary for the typist to know when this point has been reached. The bottom edge of the work sheet 4, however, is at this time generally concealed between the platen 3 and a paper shelf 7 which guides the paper to the platen. There must therefore be some outside means for enabling the typist to tell at a glance

when the limit of typewriting on a work sheet of a particular size has been reached. For this purpose, I provide a gage 8, which is mounted on the typewriter, preferably on the platen frame, in such a position that the top edge of the work sheet will be stopped from further movement when a predetermined limit of typewriting for the particular work sheet has been reached.

10 In the forms shown in the drawing, the gage is shown to comprise a standard 9, attaching means 10, and a stop 11, adjustably mounted on the standard 9. The stop is shown to be constructed of a single strip of sheet metal having openings 12 and 13 arranged adjacent the ends of the stop, and a third opening 14 arranged intermediate the openings 12 and 13. The strip of metal is bent as will be seen by reference to Figs. 4 and 5, so that the three openings 12 to 14 extend in alinement with each other, whereby the standard can be run through the three openings. It will also be noted that the end openings are brought in juxtaposition to each other, while the intermediate opening 14 is somewhat more distant from either of the end openings. This arrangement gives to the stop a spring which tends to cause the front edge 15 of the opening 12 to hug the standard 9. The arrangement also provides an extension 16 which forms with the standard 9 at the junction thereof, a stopping corner in which the top edge of the work sheet will readily catch.

35 The standard 9, as will be seen by reference to Fig. 2, is formed from a single strip of wire bent intermediate its ends to form an elongated loop having parallel reaches. These reaches are provided on their facing 40 sides with notches 17 enabling the front margin 15 of the opening 12, which is cut away at the ends thereof, as will be seen by reference to Fig. 6, to engage these notches and lock the stop 11 into any adjusted position on the standard 9. These notches, may if desired, be arranged at intervals from each other corresponding to the distance between typewritten lines under the control of the typewriting mechanism.

50 In Figs. 1 and 2, the attaching means 10 is shown to be formed integral with the standard 9, in fact, constructed of the same strip of wire; that is to say, the reaches of the standard 9 are extended and bent to form 55 loops 18, 19, and 20, which extend in planes substantially at right angles to the plane of the loop forming the standard 9. These loops are somewhat springy so that the loop 19 can be readily sprung in between a rail 21 on the platen frame 2, and a curl 22 on the paper shelf 7.

The extremities of the wire indicated at 23 may engage the back side of the shelf 7 so as to form a steadyng means, which together with the spring snap connection of

the gage to the typewriter will hold the gage firmly in position on the typewriter until forced by positive pressure out of its operative position for the purpose of disconnecting it from the typewriter.

70 The loops 18 may be secured together by a band or collar 24 adding strength to the device as a whole.

In the form shown in Figs. 7 to 9 inclusive, the attaching means instead of being formed integral with the standard 9, is constructed from a separate strip of sheet metal 26, bent to form loops similar to the loops 18, 19 and 20, and engaging the rail 21 and the curl 22 in a similar manner. In 75 this case the ends of the wire forming the standard 9 are bent inwardly as at 24 to pass in a curl 25 formed in the sheet metal attaching means 26. The standard 9 is further secured to the attaching means 26 in 80 this instance, by curls 27 and 28, embracing the reaches of the standard 9. The attaching means in this instance may be provided with an opening 29 to add to the resilience 85 thereof.

90 In the use of the device a trial sheet is first marked at a point adjacent the bottom, where it is desired to limit the typewriting. The sheet is then run in the typewriter until this mark comes to the printing point 6. The stop is then manipulated by pressing on opposite sides thereof, from the condition shown in Fig. 4, to that shown in Fig. 5, whereby it will be unlocked from the standard 9 so that it can be readily 100 adjusted until the extension 16 thereof comes in contact with the top edge of the work sheet 4, as indicated in Fig. 1. In subsequent typewriting operations, when the top edge of any sheet of the same size comes in 105 engagement with the gage, as shown in Fig. 1, it will indicate that the limit of desired typewriting on this particular work sheet has been reached.

110 When it is no longer desired to use the gage, or when it is desired to close the machine, it is merely necessary to force the gage rearwardly, when the spring loop 19 will yield sufficiently to enable the gage to be snapped off of the machine. The gage can 115 just as readily be snapped into position by pressing the spring loops 19 between the rail 21 and the edge of the curl 22.

Variations may be resorted to within the scope of the invention, and portions of the 120 improvements may be used without others.

Having thus described my invention, I claim:

1. The combination with a typewriter having a paper shelf and a rail, of a paper 125 depth gage for said typewriter secured to said typewriter, by having a portion thereof sprung in between said rail and said shelf.

2. A paper depth gage comprising a standard and a stop, said standard compris- 130

ing a pair of parallel reaches with notches on the facing sides, and said stop having means to engage said notches to lock said stop against movement along said standard.

5 3. A paper depth gage comprising a standard and a stop adjustable along said standard, said standard being formed of a single strip of wire bent intermediate its ends to form an elongated loop, and with 10 its ends bent to form a plurality of attaching loops.

4. A paper depth gage comprising a standard and a stop adjustable along said standard, said standard being formed of a 15 single strip of wire bent intermediate its ends to form an elongated loop, and with its ends bent to form a plurality of attaching loops in planes extending at angles to the plane of said first mentioned loop.

20 5. A paper depth gage comprising a standard, a stop and attaching means, said standard and said attaching means being constructed of a single strip of wire bent into form.

25 6. A paper depth gage comprising a standard and a stop adjustable along said standard, said standard being formed of a single strip of wire bent intermediate its ends to form an elongated loop, and with 30 the ends bent to form a plurality of spring loops forming means for attaching said gage to a typewriter.

7. A paper depth gage comprising a standard and a stop, said stop being formed 35 of a strip of metal having three openings therein, two of which are located adjacent the ends of said strip, and the third of which is located intermediate the end openings, said strip being bent to form a resili- 40 ent member with all openings in alinement so that said standard can pass through them.

8. A paper depth gage comprising a standard and a stop, said stop being formed of a strip of metal having three openings

therein, two of which are located adjacent 45 the ends of said strip, and the third of which is located intermediate the end openings, said strip being bent to form a resilient member with all openings in alinement and with the end openings in juxtaposition 50 to each other.

9. The combination of a typewriting machine comprising a platen frame having a paper shelf and a rod parallel with the edge of the shelf, and a paper depth gage 55 having an expandible portion adapted to enter between said rod and the paper shelf and thereby hold the gage in operative position on the machine.

10. The combination of a typewriting machine comprising a platen frame having a paper shelf and a rod parallel with said shelf and spaced therefrom, a paper depth gage having a resilient expansible portion adapted to be sprung into place between 65 said rod and paper shelf, thereby forming a snap lock connection between the gage and the platen frame.

11. The combination with a typewriting machine, comprising a platen frame having 70 a paper shelf, with a curled edge, a rod parallel to and spaced from said edge, and a paper gage having a loop of resilient material sprung in position between the edge of the paper shelf and said rod, and also 75 having an extension bearing against the paper shelf.

12. The combination of a typewriting machine having a platen frame comprising a paper shelf, and a paper depth gage hav- 80 ing a snap lock connection with the platen frame and supported by the paper shelf at a point unexposed to view.
